UNITED STATES PATENT OFFICE.

ROBERT H. WALTER, OF LOS ANGELES, CALIFORNIA, ASSIGNOR OF ONE-HALF TO SAMUEL L. KISTLER, OF LOS ANGELES, CALIFORNIA.

ACETYLENE-GAS BURNER.

SPECIFICATION forming part of Letters Patent No. 772,594, dated October 18, 1904.

Application filed February 9, 1904. Serial No. 192,817. (No model.)

To all whom it may concern:

Be it known that I, ROBERT H. WALTER, a citizen of the United States, residing at Los Angeles, in the county of Los Angeles and State of California, have invented new and useful Improvements in Acetylene-Gas Burners, of which the following is a specification.

My invention relates to a burner more especially designed to produce heat than light; and the object thereof is to produce an acetylene-gas burner of simple construction that may be used for producing heat. I accomplish this object by the burner described herein and illustrated in the accompanying drawings, in which—

Figure 1 is a vertical central longitudinal section of my improved burner. Fig. 2 is a plan of the same.

In the drawings, A is the mixing-tube, which is provided with the usual air-inlet B in the bottom thereof.

C is the usual spud which supplies the gas to the burner. The mixing-tube opens into an annular supply-chamber D, which is preferably semicircular in cross-section, as shown in Fig. 1. This chamber is preferably cast in two parts and is secured together by bolts E, the top plate being an annular plate provided with burner-tips F. These burner-tips are enlarged in the bottom portion thereof to form a submixing-chamber G, which is separated from the general mixing-chamber D by a fine gauze-wire screen H and from the outlet J by a wire-gauze screen I, which prevents back firing into the general mixing-chamber through the outlet of the burner-tip. I have found that a burner in which the general mixing-chamber is five-eighths of an inch across the top and one-half of an inch deep in the center and the outside diameter is three and one-half inches and the top plate is provided with eight burner-tips, as shown in the drawings, whose outlets are one-eighth of an inch and the air-mixing tube is one-half of an inch inside diameter, produces satisfactory results.

These proportions may be varied within reasonable limits, as will be understood by those skilled in the art.

A burner thus constructed provides a simple and efficient heat-producing acetylene-gas burner.

Having described my invention, what I claim as new, and desire to secure by Letters Patent, is—

1. An acetylene-gas burner comprising a mixing-tube having an air-inlet; a supply-chamber into which said mixing-tube opens; a plurality of burner-tips connected to and opening into said supply-chamber, each of said burner-tips having a submixing-chamber in the portion thereof opening into the supply-chamber and a constricted unobstructed outlet above the submixing-chamber; wire screening separating said submixing-chamber from said supply-chamber and said submixing-chamber from the outlet of said burner-tip.

2. In an acetylene-gas burner for producing heat; a burner-tip therefor having a constricted and unobstructed outlet at the top and a submixing-chamber below said outlet, wire screening at the top and bottom of said submixing-chamber.

3. An acetylene-gas burner comprising a mixing-tube having an air-inlet; an annular supply-chamber into which said mixing-tube opens; burner-tips connected to and opening into said supply-chamber, said burner-tips having outlets at the top and submixing-chambers in the portion thereof opening into the supply-chamber; wire screening at the top and bottom of said submixing-chamber.

In witness that I claim the foregoing I have hereunto subscribed my name this 3d day of February, 1904.

ROBERT H. WALTER.
